ADVERTISING DISPLAY DISPENSER

Leon Ridgeway Redfield, Astoria,
Long Island, N. Y.

Application April 11, 1941, Serial No. 388,109

2 Claims. (Cl. 242—55.2)

This invention relates to advertising display dispensers. It is particularly directed to dispensers for toilet paper, wrapping paper, paper towels, napkins and the like articles.

An object of this invention is to provide a dispenser of the character described, in which the paper or towel dispensed may carry advertising matter which may be seen through a transparent wall of the dispenser, and provided with means to permit easy refilling of paper within the dispenser.

A further object of this invention is to provide a dispenser of the character described having means to dispense predetermined lengths of paper, and means to positively feed the paper from the dispenser as a knob is turned by the user, means being provided to permit the paper to be threaded into the exit chute.

Yet a further object of this invention is to provide a strong, rugged, compact and durable dispenser of the character described, which shall be relatively inexpensive to manufacture, easy to manipulate, attractive in appearance, and yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which are shown various possible illustrative embodiments of this invention,

Fig. 1 is a horizontal, cross-sectional view through a dispenser embodying the invention, taken just below the top wall of the dispenser;

Fig. 2 is a cross-sectional view taken on line 2—2 of Fig. 1;

Fig. 3 is a cross-sectional view taken on line 3—3 of Fig. 1;

Fig. 4 is a cross-sectional view taken on line 4—4 of Fig. 2;

Fig. 5 is a perspective view of the improved dispenser;

Fig. 6 is a partial, elevational view of a dispenser embodying the invention, and illustrating a modified construction;

Fig. 7 is a partial, cross-sectional view taken on line 7—7 of Fig. 6;

Fig. 8 is an elevational, cross-sectional view of the upper end of the dispenser shown in Fig. 6, illustrating the pivoted top cover and the latching means therefor.

Referring now in detail to the drawings, and particularly to Figs. 1, 2, 3, 4 and 5, 10 designates a dispenser embodying the invention, for dispensing paper from a pair of rolls 11 and 12. The dispenser 10 comprises a casing 13 having a top

wall 15, parallel side walls 16 and 17 and end walls 18.

Disposed within the bottom of the casing, and welded to the lower ends of the side and end walls 16, 17 and 18, is a frame 20 of angular transverse cross-section. The frame 20 has portions 21 and 22 at the side walls 16 and 17 and portions 23 and 24 at the end walls 18. Portions 21 and 22 have horizontal inwardly extending flanges 21a and 22a, respectively, and vertical upwardly extending flanges 21b and 22b, respectively. Frame portions 23 and 24 have inwardly extending horizontal flanges 23a and 24a, respectively, and vertical upwardly extending flanges 23b and 24b, respectively. The lower end of the casing is closed by a wall 26 screwed by screws 26a to the flanges 21a, 22a, 23a and 24a.

The end walls 18 are formed with square window openings 18a, and with inwardly curved wall portions 18b all around said square openings, the inner ends 18c being channel shaped to receive transparent window panes 18d.

Fixed within the casing and disposed parallel to the end walls 18 are a pair of similar, symmetrically disposed plates 30 spaced inwardly of the transparent plates 18d, and having outwardly extending flanges 31 contacting the inner surface of the top wall 15, and welded or otherwise attached thereto.

Frame wall portions 23b carry pivot pins 32 to which are pivoted a pair of similar horizontal supports 33. The outer ends of arms 33 are notched, as at 34. The arms are held in horizontal position by screws 35 screwed to one of the walls 18. The arms 33 are formed with central bearing openings 36 to receive the lower ends 38 of shafts 37, on which are mounted the paper rolls 11 and 12. The upper ends of shafts 38 are supported by bearing members 40 attached to the underside of top wall 15.

On frame portion 23 is a horizontal ear 44 supporting the lower end of a vertical shaft 45 on which is mounted an idler roller 46. The upper end of shaft 45 is supported by an ear 47 struck from one of the walls 30. Extending from frame portion 23 is a horizontal ear 49 supporting the lower end of a vertical shaft 50 on which is mounted an idler roller 51. The upper end of shaft 50 is supported by an ear 52 struck from the other vertical wall 30. The pivoted arms 33 are adapted to contact the lower edges of the vertical plates or walls 30, as shown in Fig. 4 of the drawings.

Extending from frame portion 23 is another horizontal ear 56 supporting the lower end of a vertical shaft 57 on which is mounted an idler roller 58. The upper end of the shaft 57 is supported by an ear 59, struck from one of the plates 30.

Top wall 15 is formed with a pair of spaced

bearing openings 61 and 62, in which are rotatably mounted shafts 61a and 62a carrying knobs 61b and 62b disposed at the top of the casing. Fixed to said shafts and disposed within the casing are gears 64 and 65, respectively. The lower ends of said shafts also carry rotary discs 67 and 68, each formed with notches 67a and 68a. The plates 30 are formed with ears pivotally supporting a pair of similar, symmetrically disposed dogs 69 and 70 adapted to engage in the notches 67a and 68a, respectively. The dogs 69 and 70 are interconnected to the plates 30 by coil tension springs 71 and 72. The dogs 69 and 70 fall into the notches 67a and 68a when the knobs 61b and 62b are rotated one revolution, to limit the length of paper dispensed. After the dogs have engaged within the notches, the knobs are stopped for a while before they can again be rotated to dispense more paper.

Frame portion 23 is formed with a horizontal ear 80, formed with a bearing opening 81 and with a slot 82. Journalled in bearing opening 81 is a vertical shaft 83, the upper end of which is journalled in the bearing opening 83a in the top wall 15. Fixed to shaft 83 is a metal roller 84. Fixed to the upper end of the shaft is a pinion 85 meshing with gear 64. Extending through the slot 82, is the lower end of a vertical shaft 86. The upper end of the shaft is received within a slot 87 in the top wall 15. On shaft 86 is a rubber faced roller 88. The lower ends of shafts 86 and 83 are interconnected by coil tension spring 89 which tends to press the rollers 84 and 88 together, for the purpose hereinafter appearing. The upper ends of the shafts 86 and 83 are also interconnected by a coil tension spring 90.

It will now be understood that paper from the roll 11 passes around the idler 58, then around the idler 46, and through the chute or passage formed between plate 30 and the adjacent glass plate 18d, and between the rollers 99 and 100. Thus, rotation of the knob 62b will feed the paper by reason of rotation of roller 99 through pinion and gear 65 meshing therewith.

Extending from frame portion 24 is an ear 92, likewise formed with a bearing opening 93 and a slot 94 supporting the lower ends of parallel shafts 95 and 96. The upper end of said shafts are supported in bearing 97 and slot 98. Shaft 95 carries a roller 99 and shaft 96 carries a rubber faced roller 100. The shafts are interconnected by coil springs 101.

It will now be understood that paper from the roll 12 passes around idler roller 51 and through the passage formed between the other plate 30 and the other transparent plate 18d, and between the rollers 84 and 88. Paper from the roll 12 is fed by turning the knob 61b.

The paper from the rolls may carry advertising matter which may be seen through the windows 18d.

Walls 16 are formed with parallel slots 110 and 111 through which the paper from the rolls 12 and 11, respectively, pass out of the casing. The slots 110 and 111 register with the passages formed between the plates 30 and the transparent walls 18d.

In Figs. 6, 7 and 8 there is shown a dispenser 10a embodying the invention, and illustrating another modified construction. The dispenser

10a is similar to the dispenser 10, except that the rolls of paper are mounted on horizontal shafts instead of on vertical shafts. In other words, if the box 10 were to be placed with the wall 16 at the bottom, the relationship of the parts would be similar to the relationship of the parts of the dispenser 10a. In the dispenser 10a, however, the walls 18 are pivoted on hinges 120 at their upper ends. In such event, walls 18 carry the rubber faced rollers corresponding to the rollers 88 and 100. The walls 18 thus move away from the plates 30 to permit the paper from the roller to be threaded into the passage between the plate 30 and wall 18, when said wall is swung down to the full line position of Fig. 6.

Furthermore, the top wall 121 may be pivoted, as at 122 and locked by a latch 123 which may be key controlled. Furthermore the horizontal paper rolls 125 may be carried by shafts 126, the ends whereof are journalled in U-shaped bearings 127 fixed to the side walls 129.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. A paper dispenser comprising a casing having a top wall, side walls and end walls, and being open at the bottom, said end walls being formed with windows, a frame within the bottom of the casing and fixed to the side and end walls, a bottom wall attached to said frame, to close the bottom of said casing, a pair of arms pivoted to said frame and formed with bearing openings to receive the lower ends of vertical shafts, means on the top wall to journal the upper ends of said vertical shafts, rolls of paper on said vertical shafts, a pair of plates within said casing and spaced from said windows forming passages therewith, and means to feed paper from said rolls through said passages.

2. A paper dispenser comprising a casing having a top wall, side walls and end walls, and being open at the bottom, said end walls being formed with windows, a frame within the bottom of the casing and fixed to the side and end walls, a bottom wall attached to said frame, to close the bottom of said casing, a pair of arms pivoted to said frame and formed with bearing openings to receive the lower ends of vertical shafts, means on the top wall to journal the upper ends of said vertical shafts, rolls of paper on said vertical shafts, a pair of plates within said casing and spaced from said windows forming passages therewith, means to feed paper from said rolls through said passages, said means including a pair of rollers adjacent each passage, means to resiliently press said rollers together, and means to rotate one of each pair of rollers.

LEON RIDGEWAY REDFIELD.
